GRILLE FOR VENTILATING FAN

William P. Boyer, Grosse Ile, and Albert A. Lipsitz, Detroit, Mich., assignors to Ventrola Manufacturing Company, Owosso, Mich., a corporation of Michigan

Application September 10, 1956, Serial No. 42,886

Term of patent 14 years

(Cl. D26—7)

Fig. 3 is a sectional view taken along the line 3—3 of Fig. 1.

We claim:

The ornamental design for a grille for ventilating fan, as shown.
